UNITED STATES PATENT OFFICE.

LOUIS C. KRUMMEL, OF CLINTON, CONNECTICUT, ASSIGNOR TO CONTINENTAL CAN COMPANY, INC., OF SYRACUSE, NEW YORK, A CORPORATION OF NEW YORK.

DEVICE FOR FEEDING CAN ENDS TO A SEAMING MECHANISM.

1,194,039.

Specification of Letters Patent.

Patented Aug. 8, 1916.

Application filed March 20, 1911. Serial No. 615,571.

To all whom it may concern:

Be it known that I, LOUIS C. KRUMMEL, a citizen of the United States, residing at Clinton, in the county of Middlesex, State 5 of Connecticut, have invented certain new and useful Improvements in Devices for Feeding Can Ends to a Seaming Mechanism, of which the following is a description, reference being had to the accompanying drawing and to the letters and figures of 10 reference marked thereon.

The invention relates to new and useful improvements in devices for feeding can ends to a seaming mechanism, wherein the 15 can end is secured to the can body, preferably by a double seam.

An object of the invention is to provide devices on which a can end may be placed, which devices are moved in timed relation 20 with the parts of the seaming mechanism so as to position the can end between the can body and the seaming mechanism.

A further object of the invention is to provide means for temporarily supporting 25 the can end beneath the seaming head until said can end is engaged by the chuck of the seaming mechanism.

These and other objects will in part be obvious, and will in part be hereinafter 30 more fully described.

In the drawings which show by way of illustration one embodiment of the invention, Figure 1 is a front view of a portion of a double-seaming machine having my improvements applied thereto; Fig. 2 is a side view of the same; Fig. 3 is a side view of the supporting end-feeding device; Fig. 4 is an enlarged detail view, showing the end 35 of the carrier and the manner of supporting a can end thereby; Fig. 5 is a detail showing the position of the carrier when the ends 40 are placed thereon.

The double-seaming machine herein shown consists of a standard 1, in which is mounted 45 a shaft 2, carrying a bevel gear 3 at the forward end thereof, which bevel gear drives a second bevel gear 4 on the spindle 5, which carries a seaming head 6 at the lower end thereof. The seaming head is provided with 50 seaming rolls 7, which seaming rolls rotate with the seaming head in the usual manner.

The can bodies are carried by a support 8 which is preferably of the drum feed type, whereby the filled cans are brought one after

another to a position underneath the seaming head, where they are held stationary during the double-seaming action. The can body and can end are centered relative to each other and relative to the seaming head, by centering jaws 9, which are mounted on 55 a slide 10, which slide in turn is reciprocated by a rod 11^a. The rod 11^a is connected to an arm 11^b which is attached to the shaft 11^c. This shaft 11^c is oscillated by an arm having a roller running in a cam groove in 60 the disk 11^d. The disk 11^d is carried by a cross shaft 11^e, which in turn, is driven by a gear and worm connection with the main shaft 2. The cross shaft 11^e also carries an arm 11^f which reciprocates the seaming 65 head, and, therefore, the seaming head will be reciprocated in unison with the slide 10, carrying the centering jaws. These centering jaws and the parts for operating the same are largely similar to those shown and 70 described in the patent granted to L. C. Krummel and J. C. Taliaferro April 12, 1910, #954,976, and further detailed description of the structure and operation will 75 not be needed.

As disclosed in this patent, the filled cans are placed on the drum feed and brought one after another under the seaming head, whereby the heads or ends are double-seamed on to the can bodies, after which 80 the closed cans are discharged from the machine. Prior to my invention, it was customary to place the can end for closing the can on to the filled can as it was conveyed to the seaming station. These ends were 85 often dislodged from the can or caught by the seaming head, which materially limited the output of the machine. By my improved device, the can end may be carried directly under the seaming head and positioned relative to said seaming head and filled can. I 90 have also provided devices for temporarily holding said can end until engaged by the chuck and seated in the can body. Said end-feeding devices consist of a carrier 11, which 95 is mounted to reciprocate in a supporting bracket 12. Said carrier consists of a dovetailed plate 13, which fits in a dovetailed groove formed in the supporting plate 14, which is carried by the bracket 12. The 100 bracket 12 is secured to the standard 1 of the double-seaming machine by bolts 15. The 105 bracket 12 is secured to the standard 1 of the double-seaming machine by bolts 15.

Adjustably secured to the upper face of

the plate 13 is a bracket 16. Said bracket is slotted at 17, and a bolt 18 carried by the plate 13 extends through said slotted bracket and serves as a means for adjustably securing said bracket to said carrier plate 13. A vertical shaft 19 is mounted in a bearing bracket 20, secured to the standard of the double-seaming machine, and in a bearing 21 formed in the bracket 12. This shaft 19 at its upper end is provided with an arm 22, which carries a roller 23 running in a cam groove 24 in a disk 25, mounted on the cross shaft 11° of the double-seaming machine. This cross shaft 11°, as above noted, is driven through a gear and worm connection from the main shaft 2.

The shaft 19 at its lower end carries an arm 26, which is connected by a link 27 with the bracket 16. As the main shaft of the double-seaming machine rotates, the shaft 19 will oscillate, which will in turn reciprocate the carrier 11. The carrier 11 at its forward end is formed with a lower forwardly projecting supporting ledge 28, on which the can end 29 rests. A ledge 30 projects over the ledge 28, and serves to hold the can end in place on the ledge 28. When the carrier is retracted or moved to the extreme left, as viewed in Fig. 1, the supporting ledge 28 is opposite an edge gage 31, which is adjustably secured to the bracket 12 by a bolt 32. The can end may be placed on the supporting ledge 28 by the operator. The can end is placed underneath the ledge 30 on the supporting ledge 28, with one edge of the can end against the edge gage 31. As the shaft 19 oscillates, the carrier will move forward to the position shown in full lines in Fig. 4, which will carry the can end underneath the seaming head. The ledge 28 and overhanging ledge 30 are so proportioned that the can end is held lightly between these parts and supported so that it may be moved underneath the seaming head into sustaining jaws. The gripping of the can end by the sustaining jaws will, however, remove the can end from the supporting ledge. It will be noted that the carrier and the supporting ledge for the can end are so constructed that when the can end is supported thereon, opposite side edges of the can end are free so that they can be gripped by the supporting jaws.

55 Mounted on the bracket for supporting the centering jaws is a plate 33. Pivotedly connected with the plate 33 is a jaw 34, which is grooved at its inner face to receive the edge of the can end. A similar jaw 35 is pivoted at the other side of the centering jaws. The centering jaws are cut away at their upper face, in order to provide a space for the jaws for temporarily supporting the can ends. A spring 36 normally presses said jaws inwardly and

stops 37 limit the inward movement of said jaws. These jaws 34 and 35 are disposed in substantially the same plane as the upper face of the carrier for the can end, so that when the can end is brought underneath the seaming head, said end will be moved into the retaining grooves in said jaws 34 and 35. The can end will be temporarily supported by these jaws until the chuck on the downward movement of the seaming head engages said can end. The supporting jaws 34 and 35 will move downward with the centering jaws, in the manner described in the patent above referred to, and, therefore, the can end will be firmly held and centered over the can body which is to be closed, so that the chuck will with certainty carry the can end into the open end of the can body. The centering jaws are cut away as clearly shown in Figs. 1 and 4, so as to provide a space for the jaws 34 and 35. The can end will therefore, be centered by the portions of the centering jaws which project above and engage the can end. The jaws 34 and 35 will yield to allow this centering of the can end.

The adjustable connection between the carrier and the bracket 16 for the purpose of varying the position of the carrier for different sized can ends, whereby the carrier may be adjusted to a position so that when the carrier is at the forward end of its stroke, the can end carried thereby will be substantially centered underneath the seaming head. The edge guide 31 is also adjustable for different sized can ends.

While I have shown my carrier for can ends as adapted to receive can ends placed by hand one at a time thereon, it is obvious that said carrier may be used in connection with a support wherein can ends are stacked and automatically fed onto the device. It is also obvious that minor changes in the details of construction and arrangement of parts may be made without departing from the spirit of my invention, as set forth in the appended claims.

Having thus described my invention, what I claim as new and desire to secure by Letters Patent, is:—

1. The combination of a can support, a seaming mechanism located above said support and including a seaming head, mounted to rotate about a fixed axis and having seaming rolls, means located beneath the seaming head and supported independently thereof for receiving a can end and centering the same relative to the seaming head, a carrier having means for supporting a can end, and means for reciprocating said carrier, whereby a can end placed thereon may be carried underneath the seaming head and placed on said can end receiving means.

2. The combination of a can support, seaming mechanism including a rotating

- seaming head and seaming rollers carried thereby, devices underneath said head for centering a can end, jaws between the main portion of said centering devices and said 5 seaming head for temporarily supporting the can end, a carrier for supporting and placing a can end underneath said seaming head and in said jaws, and means for operating said carrier.
- 10 3. The combination of a can support, a seaming mechanism having a rotating seaming head and seaming rollers carried thereby, means for feeding can ends beneath said seaming head including a carrier, a supporting ledge at the forward end of said carrier upon which said can ends are adapted to rest, and means for reciprocating said carrier in timed relation to the operation of the seaming head, whereby said carrier is 15 moved forward to place a can end underneath the seaming head, when the seaming head is raised.
4. The combination of a can support, seaming mechanism having a rotating seaming head, means for feeding can ends beneath the seaming head including a reciprocating carrier, a supporting ledge at the forward end of said carrier, a rock shaft, an arm carried by said rock shaft, a link 20 connecting said arm to said carrier, and means whereby the connection between said 25 arm and said carrier may be adjusted to
- vary the reciprocating position of the carrier.
5. The combination of a can support, 35 seaming mechanism having a rotating seaming head, means for feeding can ends beneath the seaming head including a reciprocating carrier, a supporting ledge at the forward end of said carrier, a rock shaft, an 40 arm carried by said rock shaft, a link connecting said arm to said carrier, and an edge gage adjacent the end of said carrier in its retracted position for positioning a can end on said carrier. 45
6. The combination of a can support, seaming mechanism having a rotating seaming head, means for feeding can ends to the seaming head including a reciprocating carrier, a supporting ledge at the forward end 50 of said carrier, a rock shaft, an arm carried by said rock shaft, a link connecting said arm to said carrier, an edge gage adjacent the end of said carrier in its retracted position for positioning a can end on said carrier, and means whereby said edge gage 55 may be adjusted for different sized can ends.

In testimony whereof I affix my signature, in presence of two witnesses.
